[57] CLAIM

The ornamental design for a hand held fingerprint scanner for imaging and capturing a photographic image, as shown and described.

DESCRIPTION

FIG. 1 is a top, front and right side perspective view of a first embodiment of a hand held fingerprint scanner for imaging a photographic image showing our new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof; the side opposite that shown being a mirror image.

FIG. 1

FIG. 2**FIG. 3**FIG. 4

FIG. 5FIG. 6

UNITED STATES PATENT AND TRADEMARK OFFICE
CERTIFICATE OF CORRECTION

PATENT NO. : Des. 348,445
DATED : July 5, 1994
INVENTOR(S) : Fishbine et al.

It is certified that error appears in the above-identified patent and that said Letters Patent is hereby corrected as shown below:

ON THE TITLE PAGE:

At [57] CLAIM, lines 2 and 3, please delete "a hand held fingerprint scanner for imaging and capturing a photographic image", please insert -A HAND HELD FINGERPRINT SCANNER FOR IMAGING AND CAPTURING A PHOTOGRAPHIC IMAGE-.

At DESCRIPTION, lines 2 and 3, please delete "a hand held fingerprint scanner for imaging and capturing a photographic image", please insert -A HAND HELD FINGERPRINT SCANNER FOR IMAGING AND CAPTURING A PHOTOGRAPHIC IMAGE-.

Signed and Sealed this

Twenty-fifth Day of July, 1995
